QUENCH CHUTE FOR HEAT-TREATING
FURNACES

Elmer K. Hansen, Edgewood, Pa., assignor to
Westinghouse Electric & Manufacturing Com-
pany, East Pittsburgh, Pa., a corporation of
Pennsylvania

Application March 4, 1939, Serial No. 259,784

8 Claims. (Cl. 193—30)

My invention relates to heat-treating furnaces of the type having a quench-opening thru which articles, heat-treated in the furnace, are directed into a quench-tank for quenching, and is more particularly applicable where a plurality of different quenches are desired, either for taking care of different kinds of articles heat-treated separately in the furnace, or for providing different quenches at different times for the same article.

A furnace of the character to which my invention is particularly applicable usually has the quench-opening in the wall of the furnace, most commonly at the end of the bottom wall, and the heat-treated articles pass through the quench-opening into a quench-tank disposed below the opening. In common practice where more than one type of quench is required, it is customary to provide either a single quench-tank which is drained and refilled with the desired quenching liquid with every change of quench, or the quench-tank is provided with a plurality of sections, any one of which can be placed under a quench-chute by moving the quench-tank, the quench-chute terminating above the tank to permit free movement of the latter, or some other equivalent expedient is employed. However, it is frequently desirable that the quench-chute terminate below level of the quench-liquid in the quench-tank, particularly in furnaces employing a protective atmosphere to envelop the articles being heat-treated. Such construction is essential if undue contamination of the protective atmosphere by excessive leakage of air into the furnace by way of the quench-opening is to be prevented. The common structures heretofore employed permit the change from one quenching liquid to another in such cases only by awkward manipulations or unsatisfactory methods.

In accordance with my invention, I provide a sectionalized quench-chute with the ends of the sections so constructed as to provide a gas-tight sealing means between the sections. The different sections can be moved relative to each other in such a manner that the lowermost part of the chute can be raised above the top of the quench-tank, whereupon the quench-tank can be moved without interference with the quench-chute. The quench-tank can be provided with a plurality of compartments each having its own quenching liquid, and when the compartment containing the proper quenching medium is underneath the quench-opening, the sections of the quench-chute may be moved back into working

position with the lowermost section extending into the quench-tank compartment beneath it, and below the level of the liquid therein. Preferably, the quench-chute is formed of telescopically collapsible sections.

Inasmuch as the quench-chute and quench-tank for heat-treating furnaces are generally disposed below the floor level, I provide, in furtherance of my invention, an operating means above the floor level for operating the collapsible sections of the chute. By providing power means for moving the quench-tank, a change in quenching liquid can be accomplished easily and simply, and without any appreciable loss of time. However, in its operative position, the quench-chute extends below the level of the quenching liquid in the quench-tank, and, therefore, as a safety measure, I control the quench-tank moving means so that it cannot move the quench-tank unless the quench-chute has been collapsed to a position in which it will not interfere with movement of the tank. Moreover, in a furnace provided with automatic charge-conveying means in its heating chamber, I can interlock the driving means for the conveyor so that it, too, will be inoperative to dump heat-treated articles through the quench-opening while the quench-tank is being moved.

My invention involves the foregoing general objects and also involves many features of construction for the quench-chute which I deem novel and important. These novel features and other objectives of my invention will be apparent from the following description, taken in conjunction with drawings in which like numerals refer to like parts and in which,

Fig. 1 is a schematic cross-sectional view of a quench-type furnace embodying my invention;

Fig. 2 is a plan view diagrammatically showing on a condensed scale a quench-tank of two compartments;

Fig. 3 is a sectional view on an enlarged scale of my novel quench-chute;

Fig. 4 is an elevational view transverse to Fig. 3, partly in section, of the quench-chute of Fig. 3;

Fig. 5 is a top plan view of the quench-chute of Fig. 3;

Fig. 6 is an exploded, perspective view of the bottom elements of the upper section of the quench-chute of Fig. 3 and

Fig. 7 is a schematic electric wiring diagram showing the interlock control for the moving means for the quench-tank and the conveyor in the furnace.

Referring to Figure 1, a furnace 2 is supported upon suitable structural members 4 resting or imbedded in floor 6 provided with cavities 8 and 10 below each end of the furnace.

- 5 The furnace 2 may be of any appropriate type having a top wall 12, a bottom wall 14, a front-end wall 16, a rear-end wall 18 and appropriate side walls; the walls defining a heating chamber 20. The walls are constructed of suitable refractory and insulating substances as is common in the art, and the front wall is provided with an entrance opening 22, while the bottom wall is provided at the rear thereof with a quench-opening 24 defined by a suitable quench-duct 26, preferably of a heat resisting alloy. Disposed within the furnace is any suitable conveyor 28, here shown of the continuously-moving type, driven by a motor 30 through power transmitting means 32.
- 20 It is obvious that in the operation of the structure thus far described, articles to be heat-treated are disposed upon the conveyor 28 at the entrance opening 22, and are moved by the conveyor through the heating chamber 20 until they are dropped off the rear end of the furnace whereupon they fall through the quench-duct 26. In order to keep the conveyor taut a suitable stretching means 34 is disposed in the cavity 10, in accordance with well known practice.
- 25 The furnace may be heated by any suitable heating means (not shown) which may be either of the electrical resistor type or the gas-fired radiant tube type, or of any of the more common means.
- 30 The particular furnace 2 is adapted for heat-treating of the articles upon the conveyor 28 in a protective gaseous atmosphere and to this end suitable protective-gas inlets 36 are provided for conveying the gases to the heating chamber 20, and the walls of the furnace are encased in a gas-impervious metallic shell 38.
- 35 The heat-treated articles falling through quench-duct 26 continue through a quench-chute indicated in its entirety by the reference character 40, and then drop into a quench-tank 42. The quench-chute and quench-tank are disposed in the cavity 8 on the base floor of which are rails 44. The quench-tank 42 is provided with shafts 46 upon which are journaled wheels 48 riding upon the rails 44 so that the quench-tanks may be easily moved from one position to another.
- 40 The quench-tank moving means comprises a reversible electric motor 50 having a shaft 52 to which is attached a worm gear 54. The worm 54 engages a gear 56 on one end of a shaft 58 suitably supported on the bottom of cavity 8. The shaft 58 is preferably a worm which engages a nut 60 depending from the bottom of the quench-tank 42. It is manifest that by the foregoing means, the quench-tank 42 will be moved in one direction when the motor 52 rotates in a fixed direction, and that the quench-tank will move in an opposite direction when the rotation of the motor 50 is reversed.
- 45 The tank 42 is preferably provided with a plurality of compartments, and, as shown in Fig. 2, may have two compartments 62 and 64 separated by a partition 66. Each compartment is provided with its own quenching liquid, and has disposed therein a conveyor 67 for conveying out of the quench-tank any articles or charges that have dropped therein.
- 50 A suitable guiding means 67' may be disposed

in each tank for directing the articles dropping into the tank onto their respective conveyors.

As may be observed from Fig. 1, the quench-chute 40 comprises two telescopically collapsible and extensible sections 68 and 70. In the extended position of the chute, the bottom edge of the section 70 is beneath the level of the quenching-liquid in the quench-tank 42, and it is manifest, therefore, that if the quench-tank is to be moved, the section 70 must be raised out of the path of the partition 66.

Referring more particularly to Figs. 3 through 6, in accordance with my invention, the upper section 68 of the quench-chute comprises a slanted inner-tube 72 encompassed by a larger outer-tube 74, both, in this particular embodiment, being of rectangular section. A bottom closure plate 76 and a top closure plate 78 enclose the space between the inner and outer tubes 72 and 74 respectively. In view of the slanting disposition of the tube 72, the plate 78 has an aperture conforming to the size of the tube 72 and disposed toward one side of this plate, while the plate 76 has a similar aperture conforming to the opposite end of the tube 72 and also disposed to one side of the plate 76.

The plates 76 and 78 and the tubes 72 and 74 are preferably welded water-tight, so that the space 80 confined by these elements may serve as a water-jacket for cooling the quench-tube 72. To this end, a water inlet 82 and a water-outlet 84 are provided for the space 80, and it may be observed that the inlet tube 82 is disposed angularly to terminate somewhat centrally of the longer dimension of the quench-chute, and that the water-outlet 84 is on the opposite side and near the top thereof so that an efficient water circulating system within the space 80 is obtained.

The upper plate 78 is made somewhat larger than the area of tube 74 to provide flanges 86 by which the quench-chute may be secured to the furnace proper. To this end, the flanges 86 have a plurality of apertures 88 completely around their rectangular periphery, and bolts 90 extend thru the shell 38 and suitable apertures therein to provide in conjunction with nuts 92 fastening means for securing the section 68 in proper position underneath the quench-duct. A gasket 93 may be interposed between the flanges 86 and the shell 38 for a gas-tight joint.

The lower section 70 of the chute 40 has a cross-section similar to that of the outer-tube 74 of the upper section, but of a larger encompassing size so that it may be telescopically collapsible about the upper section 68. As a convenient means for raising and lowering the lower section 70, the last is provided with a plurality of spaced lugs 94 on opposite sides thereof, and secured to the upper part of the lower section, while a plurality of stub shafts 96 are similarly disposed on the upper part of the upper section 68. Sheaves 98 are loosely mounted on the shafts 96 and are maintained in position thereon by cotter pins 100 or the like. Cables 102 are fastened to the lugs 94 and pass over the sheaves 98, from whence they extend horizontally to sheaves 104, preferably disposed at the side of the furnace. The cables are then run upwardly over appropriate guiding sheaves 106 to a manually-operable drum 108, secured and rotatably mounted above the level of the floor 6. The drum is provided with a handle 110 by which it may be rotated to wind or unwind cables 102 whereby the lower section 70 may be raised or lowered in an evident

manner. In order to latch the parts in position, a latching means comprising a ratchet wheel 112 and a latch 114 is provided, the ratchet wheel 112 being secured to the drum 108 and the latch pivoted in a proper position for engaging the ratchet wheel for latching the drum.

My novel punch-chute is designed as aforesaid, for particular application to furnaces employing a protective gaseous atmosphere in its heating chamber, and to prevent either an excessive loss of atmosphere or undue contamination of the atmosphere, I provide my chute with a novel construction which results in a gas-tight sealing means between the collapsible sections. As more particularly shown in Fig. 6, the lower plate 76 has a plurality of tapped apertures 116 spaced about the periphery thereof, and a lower, apertured, trough-member 118 includes a base plate 120 having apertures 121 positioned to cooperate with the apertures 116. The base plate 120 of the trough-member 118 is of a size somewhat larger than the outside dimensions of the tube 74 of the upper chute section, but somewhat smaller than the inside dimensions of the tube 70 of the lower chute section to provide a rigid securing means by which the base 120 can be secured to the plate 76, as more particularly shown in Figs. 4 and 6. Extending upwardly from the outer edge of the base 120 is an up-standing side 122 so that when the trough-member 118 is secured to the upper section 68 of the quench-chute, in effect a trough 124 is provided which may be filled with oil or any other sealing medium. The trough-member 118, obviously, is secured to the base plate 76 by means of screws or bolts 126 fitting through the apertures 121 in the base plate 120 and secured in the threaded apertures 116 of the base plate 76. A suitable gasket 128 is interposed between the two base plates 76 and 120 to assure a gas and oil tight joint.

To complete the seal, the lower section of the quench-chute is integrally provided with an inwardly turned-over lip comprising a horizontal portion 130 and a downwardly-extending lip portion 132. The lip portion 132 is of a size to fit within the trough 124 which, when filled with a sealing medium such as oil, cooperates with the overhanging lip portion 132 of the lower section 70 to provide a gas-tight seal between the cooperating ends of the collapsible sections of the chute. Moreover, because part of the water jacket is interposed between the oil seal and the tube 72 which may be at a high temperature due to the heated articles falling therethrough, the oil in the seal will be kept relatively cool so that its efficacy as a seal will not be destroyed by deterioration or decomposition due to excessive heating. The life of the oil is accordingly practically unlimited.

In addition to serving as part of the seal, the trough-member 118 can also act as a support for the lower section 70 of the chute. In such case the cables 122 are used only in the capacity of part of the operating means for the lower section 65 of the chute. In this case, the lip 132 may rest upon the base member 120, or, alternatively, the horizontal portion 130 of the section 70 may rest on the up-standing leg 122 of the trough-member 118.

It should be observed that by securing the trough-member 118 to the closure plate 76 as I do, rather than having it integral with the tube 74, the respective sections 68 and 70 can be readily assembled into the complete chute, or the lower section removed without disturbing the upper sec-

tion 68 or any of the parts protruding therefrom. In the preferred manner of assembling and dismantling lower section 70, it is placed in a position about the upper section 68 leaving ample space beneath the two for securing or removing the trough-member 118 to or from the plate 76 as the case may be.

In accordance with common practice for construction of furnaces of the quench type that employ a protective atmosphere, I provide gas-inlet means 140 adapted to convey the gases of the protective atmosphere to the furnace at spaced points approximately along the bottom of the quench-duct 26. Any suitable number of such inlet pipes 140 may be provided. The gas admitted through the pipes 140 usually serve as a curtain to prevent any fumes from the quench rising into the heating chamber. Moreover, a plurality of exhaust pipes 142 may be provided at the upper part of the upper section of the quench-chute and below the gas inlets 140 for exhausting whatever fumes that find their way into the chute. Usually with proper spacing of the pipes, a small suction head of approximately $\frac{1}{2}$ " of water is sufficient to prevent fumes from entering the furnace, and at the same time no appreciable amount of the protective atmosphere will be drawn into the exhaust pipes along with the fumes.

It may be observed that in accordance with my invention, the water inlet pipe for the water jacket in the upper section of the chute enters in the top thereof and has the down header pipe 82 of such length and disposition as to discharge the cooling liquid at the bottom of the water jacket. The primary purpose of this construction is to provide an unobstructed path for raising the lower section 70 about the upper section 68 since, if the water inlet pipe were positioned at the bottom of the section 68, as is usual, the lower section would not then be free to rise. If desired, the bottom of the section 70 may be flared as shown at 144 adding rigidity to the bottom section, but this is obviously an optional detail of construction.

It may therefore be observed that in accordance with the objects and features of my invention, I have provided a collapsible quench-chute whose lower section 70 may be raised above the top of the tank 42, so that the tank may be moved with either compartment 62 or compartment 64 placed under the chute. All that is necessary is that the drum 108 be first wound up to raise the chute, the operating means of the motor of the quench-tank then operated to position the desired compartment under the chute, and then the latch 114 may be released to permit the lower section 70 to drop.

When the chute is in collapsible position, it is desirable that the conveyor be incapable of discharging articles for quenching, and when the chute is in extended position, it is desirable that the quench-tank be incapable of moving and possibly damaging the extended quench-chute. In order to accomplish these purposes a multiple-pole switch 146 is provided which is operated by the lower section 70 of the chute when that section is in raised or collapsible position. Referring to the wiring diagram of Fig. 7, it may be observed that the conveyor motor 30 is energized from a suitable source of power 148 through a control switch 150 and contactors 152 of the switch 146. The contactors 152 are in circuit-closing position whenever the horizontal portion 130 of the lower section 70 does not engage

the operating member 153 of the switch 146, that is, whenever the section 70 is extended. Accordingly, it is manifest that the conveyor motor 30 may be energized by closing the switch 150 whenever the quench-chute is in its proper position in the quench-tank, but cannot be energized even if the control switch 150 is closed, whenever the lower section 70 is in raised position whereby it opens the energizing circuit to the motor 30 at 10 the contactors 152.

Similarly, the contactors 154 operated by the control switch 146 control the operation of the tank-moving motor 50. However, these contactors have a position reversed to that of the 15 contactors 152, being in circuit-closing when the section 70 is in raised or collapsed position and in circuit-opening position otherwise. Thus, the power supply for the motor 50 coming from the source of energy 156 passes through a main control switch 158 through the contactors 154 and through a reversing switch 160. When the lower section 70 of the quench-chute is in a position other than in raised position, as, for example, projecting somewhat into the quench-tank, the 20 motor 50 cannot be energized since the contactors 154 are then in circuit-opening position. However, if the lower section 70 be raised to operate the switch 146, the contactors 154 will be moved against the pressure of spring 162 to circuit-closing position. If the main switch 158 is closed then by suitable operation of the reversing switch 160, to energize motor 50, either compartment 62 or 64 of the quench-tank may be placed under the quench-opening 24. Manifestly, limit 25 switches may be applied to further control the motor 50 in accordance with the position of the quench-tank so as to assure that the tank will be properly positioned under the quench-opening for whichever of its compartments is selected to 30 be employed for quenching.

While I have illustrated my invention in accordance with a preferred embodiment thereof, it is manifest that many modifications and changes may be made therein and equivalents 45 substituted without departing from the spirit of my invention. Accordingly, I desire that the appended claims be given their broadest interpretation and limited by the prior art.

I claim as my invention:

50 1. A quench-chute comprising a pair of nested tubes, top and bottom closure plates defining a cooling jacket between said tubes, said plates being apertured to correspond to the inner of said nested tubes, and a correspondingly-apertured flanged plate removably secured to said bottom plate and of larger periphery and having an upstanding flange whereby to form a sealing-trough with the outer of said tubes.

60 2. A quench-chute comprising a slanted inner tube and a surrounding substantially vertical outer tube, top and bottom cover means between the ends of said tubes and sealed thereto thereby defining a cooling jacket, water inlet and outlet means to said jacket, an upwardly-flanged plate 65 having an opening therein sufficient to encompass the lower opening of the said inner tube, and means to secure said plate substantially at the bottom of said chute whereby to form a sealing trough with said outer tube.

70 3. A quench-chute comprising a pair of telescopically collapsible sections, one of said sections comprising a pair of nested tubes, top and bottom closure plates defining a cooling jacket between said tubes, said plates being apertured to corre-

spond to the inner of said nested tubes, and a correspondingly apertured flanged plate removably secured to said bottom plate and of larger periphery whereby to form a sealing-trough with the outer of said tubes, the outer of said tubes having secured thereto about its upper end a plurality of shafts each having a sheave loosely rotatable thereon, the second of said sections comprising a tubular member larger than said outer tube, said second section having an overhanging lip adapted to enter said trough and thereby provide a seal, cable means secured to the upper end of said second section and passing over said sheaves, and means to operate said cables to raise and lower said second section. 10

4. A quench-chute comprising an upper section having a pair of nested tubes, top and bottom closure plates defining a cooling jacket between said tubes, said chute also comprising a lower section telescopically collapsible about said upper section, and liquid inlet and outlet means to said jacket, the last said means being disposed near the top of said upper section whereby not to interfere with raising of the lower section. 15

5. A quench-chute comprising an upper section having a pair of nested tubes, top and bottom closure plates defining a cooling jacket between said tubes, said chute also comprising a lower section telescopically collapsible about said upper section, liquid inlet means to said jacket, 20 disposed near the top of said upper section and including a tube inside said jacket having a discharge end near the bottom of said jacket, and liquid outlet means for said jacket disposed near the top of said upper section whereby the two 25 last-recited means do not interfere with raising of said lower section. 30

6. A quench-chute comprising an upper section having a pair of nested tubes and means enclosing the space between said tubes to provide a cooling 35 jacket, said chute also comprising a movable lower section telescopically collapsible and extensible about said upper section, liquid inlet means to said jacket comprising a pipe discharging substantially at the bottom of said jacket, 40 having all of its portions out of the path of the movement of said lower section, and liquid outlet means for said cooling jacket. 45

7. A quench-chute comprising a pair of telescopically collapsible and extensible sections, one 50 of said sections being an upper section, said upper section comprising an inner chute tube and cooling jacket for said tube, a second of said telescopically collapsible and extensible sections comprising a lower section, and cooperating means 55 substantially at the bottom of said upper section and at the top of said lower section providing a gas-seal between said sections, said seal being disposed next to said cooling jacket whereby said cooling jacket also cools said seal. 60

8. A quench-chute comprising an upper section having an inner tube and an outer tube, said tubes being nested, and having means enclosing the space between said tubes to provide a cooling jacket, said chute also comprising a lower section 65 telescopically collapsible and extensible about said upper section, cooperating means at the bottom of the upper section and at the top of said lower section for providing a gas-tight seal around said sections, the last said means comprising a trough on said upper section and flange on said lower section adapted to depend into said trough, said seal being outside said jacket. 70

ELMER K. HANSEN.
